(57) **CLAIM**

The ornamental design for cup holder for couches and sofas, as shown and described.

DESCRIPTION

FIG. 1 is a top, front, left side perspective view of a cup holder for couches and sofas showing our new design.

FIG. 2 is a right side view thereof.

FIG. 3 is rear view thereof.

FIG. 4 is front view thereof.

FIG. 5 is a top plan view thereof.

FIG. 6 is a bottom plan view thereof.

FIG. 7 is a top, front, left side view of an alternate embodiment of FIG. 1.

FIG. 8 is a right side view of FIG. 7.

FIG. 9 is a rear view of FIG. 7.

FIG. 10 is a front view of FIG. 7.

FIG. 11 is a top plan view of FIG. 7; and,

FIG. 12 is a bottom plan view of FIG. 7.

Any features shown in dotted, dashed, and/or broken lines are for illustrative purposes only and do not form part of the claimed design. Any surface shading is used solely to show the character or contour of the surface represented.

1 Claim, 12 Drawing Sheets
